UNITED STATES PATENT OFFICE.

FRANÇOIS R. MARCEL, OF BROOKLYN, NEW YORK.

PERMANENT-HAIR-WAVING PAD.

Application filed February 19, 1923. Serial No. 619,786.

To all whom it may concern:

Be it known that I, FRANÇOIS RENE MARCEL, a citizen of the United States, and a resident of the borough of Brooklyn, city 5 and State of New York, have invented certain new and useful Improvements in Permanent-Hair-Waving Pads, of which the following is a specification.

In producing what is called a permanent 10 wave in the human hair it is common practice to apply to the hair some chemical such as borax or a combination of borax and other materials, or an oily substance, which when the hair is subjected to a heating or 15 baking action will set the wave or make it permanent so that the wave will be retained for a long time, even though the hair is repeatedly washed.

One very common method of applying 20 the chemical or borax has been to make a pad composed of sheets of fabric between which the borax crystals were loosely held and in one form of pad the two sheets of fabric had rows of stitches through them to 25 form a series of pockets to prevent the loose borax from shifting around and dropping out. In this and most all former processes using borax there was always more or less borax falling out of the pads and getting 30 on the hands and clothes. In addition, the pads were manipulated only with loss of time and they were so bulky as to limit the size of the lock of hair which could be enclosed in the heater.

The object of my invention is to provide 35 a pad which will overcome each and all of these objections. I provide a pad composed of two or more sheets between which the treating material is placed and this material is mixed with and held in a binder or 40 vehicle which will remain in a plastic state until the pad is used. The pads may therefore consist of the sheets and the enclosed body of material, the whole being plastic 45 and the sheets being held by the enclosed material. The sheets may consist of pliable cardboard or of fabric, both of which are shown herein. As the pad is pliable it may be very quickly placed around the curler 50 and lock of hair. Furthermore, the pad may be handled to any extent without any of the borax or other treating material shifting or becoming loose or separating from the pad and therefore the pad is much 55 cleaner to handle. This is true even after the pad has been moistened preparatory to

being applied to the hair. As the pad is less cumbersome it does not fill the space in the heater to the same extent. If the present pad is moistened preparatory to being 60 used and if then it is found that the operator does not desire to use the pad till some future time it may be allowed to dry and it can be moistened again and be used at some future time; so that there is no waste of 65 pads where the operator prepares more than are required for any given case.

While the pads may be made in sizes such as are most commonly used for waving I 70 prefer to make it in strips of such length as to form a number of pads. From this strip each pad may be readily cut off with shears or a knife and each pad may be cut to the desired length. It is more convenient to use 75 pads of different length according to varying requirements in order that the pads may not be unnecessarily long for a particular wave and by cutting off the individual pads of lengths suitable for each use, the pads are more convenient to use and there is no 80 waste of the pad material.

The present pad remains plastic or pliable so that it is very easily handled and it is very readily wrapped around the curler and 85 lock of hair.

In the drawing forming part of this application—

Figure 1 is a perspective view of my improved pad, with parts turned back to show 90 the several layers of material.

Figure 2 is a similar view of a modified form in which one of the sheets is made of pliable cardboard, and

Figure 3 is a perspective view of the pad 95 made in the form of a strip or roll.

In Figure 1 I have shown a pad 1 composed of a sheet 2 of fabric on one surface of the chemical filler, of a sheet 3 of fabric on the other surface of the filler, and a filler 4, incorporating the particular chemical 100 which is to be used in the waving process. The adhesive properties of the filler serve to hold the parts of the pad together.

The material of the filler of the pad may consist only of borax and the binding materials or it may consist of borax and special preparations which may consist of glycerine or other oily substances mixed together. In preparing the body of filler material I mix a paste of common starch and water, 110 to which is added a gum, and for this purpose I have found gum arabic very suitable.

The borax or borax and any special materials which are to be used, is mixed thoroughly into the paste-like material. This is to form the filler of the pad, the starch and gum merely acting as a binder or vehicle for the borax. I have found, however, that when borax and the starch-gum materials are mixed together that the borax acts quite differently than when it is used alone or without the paste. In this case the borax may be moistened and dried and again moistened and it may be used in waving after the subsequent moistening. The mixture of paste and borax is very sticky or tacky and while in the moistened condition I spread it over one of the sheets of fabric placed upon a tray or support, spreading it over the sheet in an even layer. Large sheets may be spread in this manner and it is very desirable that the filler be spread over the sheet when it is first mixed; in other words, the filler should not be kept for any considerable time before being applied to the sheet. If 3 is the sheet on which the filler is first spread then when an even layer has been spread over this sheet the top sheet 2 is applied on the filler and the whole is pressed or rolled. The large body or blanket may then be cut up or it may be first allowed to dry out and then cut up. The large blanket is cut up into individual pad sizes suitable for application in waving, or, as shown in Figure 3, it may be cut into long strips 6 of sufficient length to form a number of pads, say a dozen.

After the material has dried out it remains plastic and the several layers of fabric and filler are all held together by the natural adhesive properties of the filler.

When a pad is to be used for waving it is simply moistened either with water or any special liquid solution,—and this softens the borax, and makes the pad more pliable. The pad is wrapped around the hair and curled the same as in former practice and when the whole is subjected to baking by the heater the vapors of the borax or other

chemical are given off from the pad and permeate the hair, setting or fixing the wave in the latter. If after waving a head of hair 50 the operator finds that more pads have been moistened than are necessary for the operation the unused pads may be allowed to dry and they may be used at some later time for another waving operation,—thus, there 55 need be no waste in using the improved pad.

The most important feature is the making of a pad of a plastic nature which requires no stitching but which is in fact held together by the filler. 60

Having described my invention, what I claim is:—

1. A pad for permanent hair waving comprising sheets of covering material and a filler between the sheets which filler embodies the material for setting the wave in the hair, and a binder of starchy material, said sheets and filler being held together as a unit by the adhesive properties of said filler. 70

2. A pad for permanent hair waving comprising sheets of covering material and a filler between the sheets which filler embodies the material for setting the wave in the hair, and a binder composed of starchy material and a gum, said sheets and filler being held together as a unit by the adhesive properties of said filler and the pad as a whole being plastic. 75

3. A pad strip for permanent hair waving comprising sheets of covering material and a filler between the sheets, which filler embodies the material for setting the wave in the hair, said sheets and filler being held together as a unit by the adhesive properties 85 of said filler, the pad strip as a whole being plastic and made of sufficient length to form a number of individual pads, whereby said strip may be cut off at any place into lengths 90 suitable to form individual pads. 90

Signed at the city, county and State of New York, this 9th day of February, 1923.

FRANÇOIS R. MARCEL.
